(57) **CLAIM**

The ornamental design for a sink saddle, as shown and described.

DESCRIPTION

FIG. 1 is a perspective view of the sink saddle of my new design showing it positioned around the base of a water faucet extending upward from a sink. The sink and other articles are shown in broken lines.

FIG. 2. Is another perspective thereof.

FIG. 3 is an elevational view of the front thereof.

FIG. 4 is an elevational view of the back thereof.

FIG. 5 is a left side elevational view thereof.

FIG. 6 is a right side elevational view thereof.

FIG. 7 is a top plan view thereof; and,

FIG. 8 is a bottom plan view thereof.

The broken line figures in FIG. 1, showing portions of a sink, a faucet, and other items are environmental, and form no part of my new design.
